BULB-STRETCHING MACHINE

Charles Eisler, South Orange, N. J.

Application June 4, 1952, Serial No. 291,679

3 Claims. (Cl. 49—22)

1

This invention relates to improvements in a machine for stretching bulbs and is adapted for use in connection with bulb-forming mechanisms having a plurality of stations, such as, for example, the type wherein the bulbs are advanced from station to station.

Pursuant to the present invention, hereinafter more particularly described and shown in the accompanying drawings, a bulb-stretching machine is provided having novel means for the stretching of bulbs to conform to predetermined final dimensions.

These and other advantageous objects, which will appear from the drawings and from the description hereinafter, are accomplished by the structure of my invention, of which certain embodiments are illustrated in the drawings. It will be apparent, from a consideration of said drawings and the following description, that the invention may be embodied in other forms suggested thereby; such other forms as come within the scope of the appended claims are to be considered within the scope and purview of the instant invention.

In the drawings:

Fig. 1 is a vertical elevational view, partly sectional, of a bulb-stretching machine embodying the invention, with the bulb to be stretched positioned therein.

Fig. 2 is a top plan view of the supporting arm portion of said machine.

Fig. 3 is a fragmentary elevational view of the invention showing the spreader bars moved apart in the bulb-stretching operation.

Fig. 4 is a perspective view of one form of said spreader bars which may be used in carrying out the invention.

Fig. 5 is an end elevational view of the casing and spreader bar portions of the machine of this invention and,

Fig. 6 is a transverse sectional view taken on line 6—6 of Fig. 3 of the bulb only stretched pursuant to the invention.

The invention is adapted for use in connection with bulb-forming machines such as, for example, are shown in my Patents Nos. 2,421,929 of June 10, 1947, and 2,418,763 of April 8, 1947, having a plurality of heads or stations, as, for example, stations A to H of the machine shown in the last mentioned patent, and provided with suitable burners, as, for example, the burners 28 of the last mentioned patent, for the purpose of softening the glass bulbs during the cycles of rotation thereof. The drawings of the present application illustrate a station which may be

2

one of a number of such stations in a machine of the class above described.

The sprocket 10 of the drawings of this application may be considered to correspond with the sprocket 41 of the drawings of my Patent 2,447,569 of August 24, 1948, and driven by suitable means such as indicated at 40 in said patent or with driver 36 and driven member 34 of my Patent 2,409,423 of October 15, 1946. The plunger 11 of the mechanism of the present invention is adapted to be reciprocated by any means suitable for that purpose, as, for example, by juxtaposing the lower end of the plunger on a cam track 12 which may be considered to correspond with cam track 58 in my Patent 2,447,569 of August 24, 1948, the arrangement of the cam track being such that it will be higher at certain stations of the machine than at others so as to effect reciprocation of the plunger 11 at the desired stations and for the purpose of the present invention.

As shown in the drawings of this application, bulb 13, which is to be stretched from the initial form thereof shown in Fig. 2 to a different cross section such as that shown at 47 in Fig. 6 pursuant to the invention is pendantly supported on a standard 14 which may be secured to the casing 15, as shown in Fig. 1 of the drawings, or to a fixture 16, as shown in Fig. 3, independent of the sprocket 10 and secured to a different part 15 of the mechanism in association with which the invention is used, as, for example, a fixture such as that shown at 44 in Fig. 3 of my Patent No. 2,553,135 of May 15, 1951. An elongated tube 17 is secured to sprocket 10 and provided with an aperture 18 therethrough wherein the plunger is adapted to vertically reciprocate, as indicated by arrow 19 of Fig. 3, responsive to a means such as cam track 12 engaging the end of the plunger 11 which projects from the lower end of the tube 17. Plunger 11 is provided at its upper end with a head 20 which projects into the transverse opening 25 in the casing 15, the latter having its sides extending laterally beyond the plunger 11. Spreader bars 26, 26' are slidably disposed in the transverse opening 25 of the casing, said bars having finger uprights 27, 27' projecting upwardly out of the casing and in the axial plane of the plunger 11. The base portions 28, 28' of the spreader bars have recessed portions 29, 29' to receive the head 20 of the plunger.

Spring means 30, 30' engage the bars and casing to normally urge the bars together and into engagement with the head of the plunger. Vertical reciprocation of the plunger 11 projects 55 the head thereof into the casing, moving the

spreader bars 26, 26' apart against the tension of the spring means to stretch the bulb positioned thereon, as shown in Fig. 3. The top of the transverse opening 25 of the casing is closed by cover plate 34 fixed to the casing by suitable means, as, for example, bolts 35. The base portions 28, 28' of the spreader bars 26, 26' are preferably provided with shoulder portions 36, 36' to engage stop portions 37, 37' of the casing. The springs 30, 30' are preferably positioned within longitudinal recesses 38, 38' in the casing, closed by threaded plugs 39, 39' or the like.

In operation, one bulb 13 is positioned over the preferably tapered upper ends 40, 40' and onto the finger uprights 27, 27', and held in axial registry with the plunger 11 by the standard 14 which, in the form shown in Fig. 1 of the drawings, may be secured at its lower end of the casing 15.

A supporting arm 41 is fixed at one end to the standard and extends therefrom toward the axial plane of the spreader bars. Spring plates 42, 43 are fixed to the arm and project from the sides thereof therebeyond to engage the bulb and hold it against the supporting arm and upon the spreader bar fingers. The free end 44 of the arm 41 is preferably of such outline that it will engage and steady the bulb. The free ends 45, 46 of the spring plates 42, 43 are preferably conformed to the cross-section of the bulb (Fig. 2). Standard 14 may be secured to a part of the apparatus or machine in connection with which the invention is used other than that shown in Fig. 1. In the form shown in Fig. 3, the standard is indicated to be a part 16 integral with or secured to another part of the apparatus or machine in connection with which the invention is used.

Having thus described my invention, what I claim as new and desire to secure by Letters Patent is:

1. A bulb-stretching machine comprising an elongated tube, having an axial aperture therethrough, a plunger slidably disposed in said aperture, the lower end of the plunger adapted to project from the lower end of the tube for engagement by reciprocating means, a rounded head at the upper end of the plunger adapted

to be projected beyond the upper end of the tube on reciprocation of the plunger, a casing secured to the upper end of the tube and having sides extending laterally therebeyond, spreader bars having base portions slidably disposed in said casing and having finger uprights disposed upwardly and outwardly of the casing in the axial plane of said plunger to receive the bulb to be stretched, and means engaging the bars and casing to normally urge the bars together and into engagement with the head of the plunger said base portions having complementary recessed portions so that, when said spreader bars are urged together, they will define a conically recessed portion to receive the plunger head, and will cooperate with the rounded head of the plunger when the latter is moved into engagement therewith, whereby, on vertical reciprocation of the plunger to project the head thereof into the casing, said spreader bars will be moved apart against the tension of said spring means, to stretch the bulb positioned thereon.

2. In a bulb-stretching machine as set forth in claim 1, a standard fixed to said casing, a supporting arm fixed at one end to said standard and extending toward the axial plane of said spreader bars, and spring plates fixed to the sides of said arm and projecting therebeyond to engage the bulb and hold it against the supporting arm and on the spreader bar fingers.

3. In a bulb-stretching machine as set forth in claim 1, a standard fixed to said casing, an arm fixed to said standard and extending therefrom toward the axial plane of said spreader bars; the free end of said arm being of such outline as to engage and steady the bulb, and spring means on said arm to hold the bulb against said free end under tension.

40. References Cited in the file of this patent.
